UNITED STATES PATENT OFFICE.

PIRMIN KOEPPFER AND HERMAN KOEPPFER, OF FOND DU LAC, WISCONSIN.

BOB-SLED.

SPECIFICATION forming part of Letters Patent No. 291,744, dated January 8, 1884.

Application filed September 10, 1883. (No model.)

To all whom it may concern:

Be it known that we, PIRMIN KOEPPFER and HERMAN KOEPPFER, of Fond du Lac, in the county of Fond du Lac, and in the State of 5 Wisconsin, have invented certain new and useful Improvements in Sleighs; and we do hereby declare that the following is a full, clear, and exact description thereof.

Our invention relates to improvements in 10 sleigh-bobs, and will be fully described hereinafter.

In the drawings, Figure 1 is a side elevation of a sleigh-bob, showing our improvements. Figs. 2 and 3 are sectional views, showing details of same.

A indicates the runners, B the knees, and C the cross-beam. Said knees B are provided on both their inner and outer faces with braces D, fastened on same by rivets or bolts. These 20 braces have their upper ends bent out at right angles and rounded to form trunnions b, and move freely in box-bearings a, bolted on the under side of said beam C on each side of the knees B. The upper end of said knees is inserted, as usual, in the mortise of the cross-beam C; but in our sleigh-bob said end of knees is formed so that said cross-beam is permitted a rocking motion on same. This is effected by making the front and rear faces of 25 said knees beveling toward each other up to their top, and cutting the mortise square through on its corresponding faces. Said cross-beam, mortise, and front and rear faces of knees end are provided with metal plates 30 b' b', to protect the wood of said parts. The flat iron raves E, bolted to the runners A at b² b², have, in about their center, a long hole or slot for lug e, formed in the flanged metal

plate F, screwed or bolted on the upper face of said cross-beam C. This plate serves as a 40 way for said raves E, the slot allowing but also limiting the rocking motion of the beam. The way between the flanges of said plate F is curved down on both sides from the center of lug e for the same purpose. The braces D 45 are thus made to strengthen the knees B on the runners A and to support the cross-beam in a manner to secure a ready adaptation of said runners to the inequalities of the roadway, without in the least distorting the body of the 50 sleigh.

Having thus described our invention, what we claim as new, and desire to secure by Letters Patent, is—

1. In a sleigh-bob, the combination, with 55 the runners A and knees B, of the mortise cross-beam C, provided with the bearings a on the under side, and the metal braces D, securely bolted to the runners and to the knees, and having trunnioned ends fitted within said 60 bearings, substantially as set forth.

2. In a sleigh-bob, the raves E, having long hole or slot in about their center, in combination with the cross-beam C, having flanged metal plates F, in center of which lug e is 65 formed for said hole or slot in raves E, substantially as shown and described, and for the purpose set forth.

In testimony that we claim the foregoing we have hereunto set our hands, on this 3d day of 70 August, 1883, in the presence of two witnesses.

PIRMIN KOEPPFER.

HERMAN KOEPPFER.
